UNITED STATES PATENT OFFICE.

HOWARD C. NOTT AND ALEXANDER W. RAU, OF NEW YORK, N. Y.

REFRIGERATOR.

No. 873,887.

Specification of Letters Patent.

Patented Dec. 17, 1907.

Application filed January 14, 1907. Serial No. 352,068.

To all whom it may concern:

Be it known that we, HOWARD C. NOTT, a citizen of the United States, residing at New York, in the county of Kings and State of New York, and ALEXANDER W. RAU, a citizen of the United States, residing at New York, in the county of Kings and State of New York, have invented certain new and useful Improvements in Refrigerators, of which the following is a specification.

This invention relates to cooling devices especially to the form generally known as refrigerators.

The object of the invention is to make use of the water from the melting ice to cause it to circulate through various portions of the refrigerator used for the storage of food and drink, whereby the said water is caused to abstract heat by extended circulation through the refrigerator and thereby render more efficient its cooling properties.

In the drawings illustrating one embodiment of our invention, Figure 1 is a front elevation. Fig. 2 is a horizontal section on line 2—2 indicated in Fig. 3. Fig. 3 is a vertical section on the line 3—3 indicated in Fig. 2. Fig. 4 is a vertical section on the line 4—4 indicated in Fig. 2; and Fig. 5 is a perspective view of the interior cooling element removed from the casing.

The invention is shown as applied to a household refrigerator, in which are shown two pairs of doors 12 and 13, opening to the storage compartment; and doors 14 and 15 are shown giving access to the ice chamber or receptacle. A hinged top 16 is also shown; all of which members are hinged to a frame member denoted generally by 17, and which may be of any desired construction.

The refrigerator is shown as provided with two shelves denoted generally by 20 and 21 that are constituted by tubes through which the water from the melting ice is caused to pass. In the form illustrated, the ice is placed in a receptacle 22, and upright tubes at each end, or each side of the refrigerator convey the water from the melting ice in the receptacle 22, into the tubes forming the shelf members; the vertical side tubular members being denoted generally by 23 and 24. These side members connect with a closed bottom vessel 25, in which the water from the melting ice in the receptacle 22 is received. A tubular member is arranged at the rear of the receiving compartment and also receives the water from the melting ice,

being connected with the closed vessel 25, and provided with an outlet member 27. The latter member conducts the water into a vessel 28 resting on the bottom 29 of the casing, to still further retain the water, until this vessel becomes filled, when the water may be drawn off by a suitable valve or faucet 30. The rear tubular member is composed of upright tubes 34 each connecting with the closed vessel 25 and opening at the top into the transverse tube 35, the latter discharging through the outlet tube 27, into the closed vessel 28.

The ice receptacle 22 is formed in the nature of a pan, having a short front wall 31, and the side tubes 32 project upwardly in the receptacle a short distance, as shown in Figs. 3 and 5, thereby causing the water from the melting ice to remain in the receptacle until its level reaches the top of the tubes 32, when it will flow down therethrough. By this means, sediment from the melting ice will be precipitated in the receptacle instead of passing down the side tubular members. The shelves 20 and 21 are formed of tubes 33 each connecting with one of the vertical tubes 32 at its extremity.

The tube 35 connecting the upright rear tubes 34 at their top is placed below the bottom of the ice receptacle 22, whereby the water filling the upright side and rear tubes and the closed vessel 25 will flow through the connecting tube 35 down the outlet 27. Thereby all of these tubes as well as the horizontal shelf tubes 33 will be filled with the cooling water and the circulation thereof established, that will serve to efficiently abstract the heat from the articles placed on the shelves and on the closed bottom member 25. The outlet tube 27 has its open end in the vessel 28 arranged near the bottom thereof, and the vessel 28 being kept practically filled, air is prevented from entering the pipe 27. The ice receptacle 22 is shown offset or removed from the rear wall of the casing and if desired, apertures 37 may be formed in the receptacle to permit a circulation of cold air from the ice box downwardly.

In the construction illustrated, it will be observed that the closed bottom vessel is rigidly connected to the ice receptacle by means of the side tube members 32, thereby constituting a rigid unit member. This member can be formed separate from the casing of the refrigerator to be inserted into the casing as may be found convenient.

The member can also be manufactured and supplied to the trade to be inserted in existing forms of refrigerators, it being only necessary to remove the shelves and the ice receptacle with its shelves or partitions, to permit the substitution of the unit interior member.

Having thus described our invention, we claim:

- 10 1. In a cooling apparatus, the combination of a closed bottom vessel, two series of parallel tubes projecting upward from the vessel, an ice receptacle connected with the upper ends of the vertical pipes one series on each of two opposite sides thereof, a plurality of series of horizontal tubes each series having a tube extending from one of said vertical tubes to a corresponding opposite tube, a series of tubes extending vertically upward from the bottom vessel at the rear thereof, a horizontal tube connecting the upper end of the latter upright tubes, and an upright outlet tube for the latter horizontal tube.
- 15 2. In a cooling apparatus, the combination of a closed bottom vessel, two series of parallel tubes projecting upward from the vessel, an ice receptacle connected with the upper ends of the vertical pipes one series on each of two opposite sides thereof, a plurality of series of horizontal tubes each series having a tube extending from one of said vertical tubes to a corresponding opposite tube, a
- 20
- 25
- 30

series of tubes extending vertically upward from the bottom vessel at the rear thereof, a horizontal tube connecting the upper end 35 of the latter upright tubes, an upright outlet tube for the latter horizontal tube, and a second closed vessel located below said bottom vessel, with said outlet tube leading into the lower portion thereof.

3. In a cooling apparatus, the combination of a closed bottom vessel, two series of parallel tubes projecting upward from the vessel, one series on each of two opposite sides thereof, a plurality of series of horizontal 45 tubes each series having a tube extending from one of said vertical tubes to a corresponding opposite tube, a series of tubes extending vertically upward from the bottom vessel at the rear thereof, a horizontal tube 50 connecting the upper end of the latter upright tubes, an upright outlet tube for the latter horizontal tube, an ice receptacle connected with the upper ends of said opposite series of vertical tubes with the bottom of 55 such vessel located above the said horizontal connecting tube, the ends of the said vertical tubes projecting a short distance above the bottom of the ice receptacle.
